UNITED STATES PATENT OFFICE.

WALTER E. DOTY, OF LOCKPORT, NEW YORK.

CHAIN-PUMP BUCKET.

SPECIFICATION forming part of Letters Patent No. 247,622, dated September 27, 1881.

Application filed February 28, 1881. (Model.)

To all whom it may concern:

Be it known that I, WALTER E. DOTY, of Lockport, of Niagara county, in the State of New York, have invented new and useful Improvements in Chain-Pump Buckets, of which 5 the following is a full, clear, and exact description.

This invention relates to that class of chain-pump buckets wherein the bucket is formed 10 of a disk or disks of vulcanite secured between two shackles of metal; and it consists, first, in a soft-rubber cushion interposed between the bucket-disk of harder vulcanite and its support; second, in the manner of attracting and 15 locking together the parts of the iron shackles.

That others may fully understand the invention, I will particularly describe it, having reference to the accompanying drawings, wherein Figure 1 represents, in perspective, plan, and 20 section, the several pieces detached. Fig. 2 is a vertical section, showing the several parts assembled. Fig. 3 is a horizontal section of the upper part of the shackle. Fig. 4 is a vertical section of the same.

25 The shackle is in two parts, A B. The part A has an eye, *a*, at one end, a flange-plate, *e*, at its middle, and a T or cross head, *d*, at its other end. The stem or shaft holds the vulcanite disks, while the cross-head *d* enters 30 the part B and clamps said disks between the flange *e* and the part B. The part B has a concave or hollow conical flange, *b*, and a loop, *e*. At the center of said flange there is an elliptical opening, *g*; adapted to receive the cross-head *d*, and on opposite side of the same 35 are inclined ways *h*, terminating at top with notches *i*.

When the cross-head is inserted in the opening *g* and the two parts rotated in opposite directions the ends of the cross-head engage on the ways *h*, and are forced to travel up there, thereby drawing the parts together until they slip into the notches *i*, and when the elastic bucket-disks are in place the parts cannot be 40 disengaged without an exertion of force equal to that which forced them into lock.

The principal bucket-disk *H* is simply a disk of vulcanite, and may be cut from sheets of

that material; or, if preferred, it may be molded. Disks or buttons of vulcanite have been 50 heretofore employed for pump-buckets, but generally with the rigidity so great that too much power is required to force them into shape.

By my invention I overcome and obviate this difficulty by placing between the disk *H* 55 and its support, on one side, a cushion, *I*, of soft elastic rubber, which will yield with sufficient ease to permit the parts to be secured, and still present sufficient resistance to hold them securely locked, and to force the disk *H* into 60 form.

I prefer to place between the cushion *I* and the flange *e* a button of vulcanite, *J*; but this may be dispensed with, if desired, the stem of A being made shorter to correspond, or the 65 buttons *I* and *J* may be molded in a single piece.

The advantages of this shackle are, besides cheapness and efficiency, the very material one of ease of disconnection and reconnection without risk of twisting the chain.

Having described my invention, what I claim as new is—

1. A chain-pump bucket composed of a metallic shackle in two parts, combined with a 75 vulcanite disk, *H*, and a soft-rubber cushion interposed on one side between said disk and its support, for the purpose set forth.

2. A chain-pump bucket composed of a metallic shackle in two parts, one of them having 80 a concave or hollow conical flange, *b*, combined with a vulcanite disk, *H*, a soft-rubber cushion, *I*, and a vulcanite button, *J*, substantially as described.

3. A shackle for a chain-pump bucket, composed of the part A, provided with loop *a* at one end, flange *e* at the middle, and cross-head *d* at the other end, combined with the part B, provided with the hollow conical or concave flange *b*, opening *g*, inclines *h*, notches *i*, and 90 loop *e*, and the vulcanite disks, substantially as set forth.

WALTER E. DOTY.
